UNITED STATES PATENT OFFICE.

LESTER KIRSCHBRAUN, OF CHICAGO, ILLINOIS.

PROCESS OF TREATING BITUMINOUS COMPOSITIONS.

1,188,081.

Specification of Letters Patent. Patented June 20, 1916.

Application filed June 18, 1914. Serial No. 845,798.

To all whom it may concern:

Be it known that I, LESTER KIRSCHBRAUN, a citizen of the United States, residing in the city of Chicago, county of Cook, and State of Illinois, have invented certain new and useful Improvements in Processes of Treating Bituminous Compositions, of which the following is a specification.

This invention relates to improvements in processes of treating bituminous composition and has among its salient objects to provide a process for regenerating old or used bituminous compositions such as sheet asphalt pavements, asphaltic concrete pavements of analogous compositions of stone, sand, and bituminous binder; to provide an improved process of obtaining the result last mentioned in such a way as to avoid burning, overheating or otherwise injuring the bituminous or asphaltic binder of such composition; to provide a process of the character referred to in which the bituminous composition in question is regenerated by the use of superheated steam; and in general to provide an improved process of the character referred to.

The invention consists in the matters hereinafter described and more particularly pointed out in the appended claims.

In the drawings—Figure 1 is a side elevation with parts broken out and shown in section of an apparatus suitable for carrying out my invention. Fig. 2 is a transverse vertical sectional view of the same.

As is well known, asphalt pavements are practically universally used through the United States. These asphalt pavements are composed of a mixture of stone, sand, mineral powders and bituminous binder, the proportion of the mixture varying with the character of the pavement and the conditions in any particular case. Annually, millions of square yards of these pavements must be repaired or replaced because either they are worn out or because of faulty construction. One of the chief causes which necessitates the replacing of or repairing of old pavements is the hardening of the bituminous binder, which in itself generally does not exceed ten per cent. of the composition. The other ninety per cent. composes the mineral aggregate, and this is practically unchanged through any period of time. Heretofore, it has been necessary when a new pavement is to be laid, to first take up and abandon the old pavement, includ-

ing not only the bituminous binder but the mineral part of the composition as well, and this was true despite the fact that the mineral aggregate of such old composition was just as good as when first laid. The difficulty has been that heretofore no successful method has been devised or used for softening and disintegrating the pavement by heat without at the same time injuring and destroying the bituminous constituents of the pavement. The value of a process which would permit the reuse of a paving composition as to its mineral composition as well as a greater part of the binder is apparent and the necessity and advantage of such a process is well recognized in the art.

I am aware that attempts have been made to devise such a method but heretofore none of these methods have been commercially successful. By the present invention, old paving composition is acted upon by a non-oxidizing agent and in such a way that the bituminous binder therein is raised to a temperature above its melting point, yet below that at which it will be injured, thereby allowing the paving composition to soften and disintegrate and acquire a degree of plasticity at which it may be raked and spread as a covering in the usual manner. If the old paving composition contains a bituminous binder which has become much hardened through the process of time or so the binder does not possess sufficient cementing powers, the hot softened disintegrated composition as above prepared may have added to it during the process a sufficient amount of fresh binder to soften the metamorphosed material in the old composition.

In carrying out my improved process the old paving composition is removed and broken up into relatively small particles. This broken up composition is placed into a retort or kiln which preferably takes the form of a horizontal cylindrical drum. The material within the drum is agitated and propelled forward in the drum either by vanes or by rotating the drum or by both. The drum is preferably mounted above a cradle of steam pipes, the steam in which is superheated by means of a furnace beneath. This superheated steam is injected into the retort or drum and heats and softens the bituminous composition. Care must be taken to prevent the contents of the drum from being overheated. In other words, if

the heat or flames of the furnace are applied directly to the drum, the latter will become overheated and the contents of the drum injured. The fresh material may be 5 continuously fed to the drum, the material being introduced at one end and delivered from the other end. The temperature of the superheated steam will be upward of 400° F., and may reach 700° or more. The 10 contents of the drum however only need to be softened enough to melt the binder which in most cases would not be in excess of 300° F.

Referring now to the apparatus shown in 15 the drawings—1 designates a furnace in the upper end of which is supported a cylindrical drum 2. Around the lower side of this drum 2 is arranged a plurality of coils or steam pipes 3 having an inlet branch 4 leading to the boiler and an outlet branch 5 as shown at 6 which communicates with the rear or delivery end of the drum. These steam pipes 3 are arranged as shown 20 in the drawing and form in effect a protecting wall between the fire of the furnace and the shell of the drum. The object of this construction is to provide not only means for superheating the steam as it passes from the boiler to the drum, but also to 25 protect the drum and its contents from the direct action of the heat of the furnace. If some means were not provided for protecting the shell of the drum against the action of the furnace, the drum would be 30 come over-heated and injure the bituminous binder of the composition which is being treated. Within the drum is suitably mounted a shaft 7 driven from any suitable gearing 8. On this shaft is mounted a series 35 of conveyer blades or teeth 9 which are or may be similar in construction to the teeth of a pug mill mixer used in mixing asphalt. The material is fed through an inlet hopper 10 into the inlet or front end of the drum, 40 and is delivered from an outlet or discharge orifice 11 in the rear end of the drum. The arrangement of this conveyer is such that the material is slowly carried from the inlet end of the drum to the discharge end thereof. 45 The teeth or blades of this conveyer closely approach the periphery of the drum so as to scrape off any material which may have a tendency to lodge on the wall of the drum. This conveyer also tends to agitate 50 and comminute or still further break up the material so that it will be more uniformly exposed to the heat of the non-oxidizing agent, to-wit, the superheated steam. By means of this combined agitator and conveyer the material will be more effectively 55 exposed to the action of the heat. Preferably the steam is taken out of the retort by means of an exhaust fan 12 connected by a pipe 13 to the drum at the base of the hopper 60 per 10.

In certain instances it may be desirable to close up the inlet and discharge orifices of the retort. Accordingly, the hopper is provided with a weighted damper 14 of well known construction. This damper is 70 so arranged that the inlet passage is closed except when the weight of the material freshly charged is forced into it. It also should be arranged so that the orifice of the inlet passage of the hopper may be constricted. The discharge passage is controlled by a damper 15. A cut off valve 16 may be interposed in the pipe 13 if desired. By closing the valve 13 and dampers 14 and 15 the non-oxidizing agent may be introduced into the retort and the material treated under pressure. A valve 17 may be interposed in the discharge branch 5 and a check valve 18 in inlet pipe 4 leading from the boiler. The furnace is provided with a 85 suitable chimney 19.

This process may also be utilized for softening rock asphalts, and the like, natural bituminous compositions, mastics, and special bituminous compositions in which 90 the filler may consist of cork, woody matters, and materials of like nature.

I claim as my invention:

1. A process of treating old or used bituminous pavements which consists in breaking the pavement up into relatively small particles, agitating and further comminuting said material in a suitable retort, moving said material from the inlet end to the discharge end of said retort, feeding fresh material to said retort, and during said operations subjecting said material to the action of blasts of highly superheated steam and heating the bituminous binder above its melting point, and continuing the 100 treatment until the binder is softened but without injury to the binder.

2. A process of treating bituminous compositions which consists in breaking up said composition into relatively small particles, then subjecting said material to the action of blasts of superheated steam, bringing the superheated steam into intimate contact with said particles to soften the bituminous binder, whereby the mineral aggregate and 110 binder can be reused, and mixing fresh bituminous material with the old.

3. A process of treating bituminous compositions composed of a non-bituminous aggregate and a bituminous binder, which 115 consists in breaking up said compositions, blasting the same in a suitable receptacle by subjecting it to the action of highly superheated steam at temperatures above 400° F., and continuing the process until the composition is softened without injury to the binder so that it may be reused or mixed with fresh bitumens.

4. A process of treating bituminous compositions composed of a non-bituminous ag- 120

gregate and a bituminous binder, which consists in heating said material in a suitable receptacle and introducing into said receptacle highly superheated steam and 5 maintaining a pressure above atmospheric on the contents of said receptacle during said treatment.

5. The process of treating bituminous compositions composed of a non-bituminous aggregate and a bituminous binder which 10 consists in subjecting the same to the action of heat in a suitable receptacle which is externally heated by the action of steam and also passing superheated steam through said 15 receptacle and continuing the process until the composition is softened without injury to the binder so that it may be reused.

6. A process of treating bituminous compositions composed of a non-bituminous aggregate and a bituminous binder which con- 20

sists in subjecting said compositions in a suitable receptacle to heat produced by passing super-heated steam through said receptacle, whereby the bituminous binder of said composition is softened, and thus permit- 25 ting the composition to be re-used.

7. The process of treating bituminous compositions composed of a non-bituminous aggregate and a bituminous binder which consists in subjecting said compositions in 30 a receptacle to the action of heat produced partially by passing superheated steam through the receptacle and partially by heating the receptacle externally with jacketed steam interposed between the receptacle 35 and a suitable fire-box.
